UNITED STATES PATENT OFFICE.

EDMUND A. PARKER, OF WEST MERIDEN, CONNECTICUT.

BOTTLE-STOPPER.

SPECIFICATION forming part of Letters Patent No. 231,678, dated August 31, 1880.
Application filed May 6, 1880. (No model.)

To all whom it may concern:

Be it known that I, EDMUND A. PARKER, of West Meriden, in the county of New Haven and State of Connecticut, have invented a new 5 Improvement in Bottle-Stoppers; and I do hereby declare the following, when taken in connection with the accompanying drawings and the letters of reference marked thereon, to be a full, clear, and exact description of the 10 same, and which said drawings constitute part of this specification, and represent, in—

Figure 1, a side view of the stopper as applied to the bottle; Fig. 2, a vertical central section of the stopper detached; Fig. 3, a perspective view of the two parts of the cork of 15 which the stopper is formed.

This invention relates to an improvement in cork stoppers for bottles.

In the usual construction the use of corks 20 necessitates a corkscrew to remove them from the bottle. This generally destroys the stopper, so that it is unfit for use. Either it will break the cork or pierce it, so that it is no longer a complete stopper for the bottle. Again, larger-sized stoppers require correspondingly large 25 cork from which to produce them, and very much waste in the manufacture of such corks is unavoidable.

The object of this invention is to use smaller 30 pieces from which to make corks, as well as to provide the cork with means for withdrawing it from the bottle; and it consists in the construction, as hereinafter described, and particularly recited in the claim.

35 The cork is made from two half-cylinders, A B, which together form the required size and shape, the division being longitudinally through the center. C is a disk, of metal or other suitable material, of smaller diameter 40 than the two parts combined. To this is attached a wire, D, cord, or similar material, preferably doubled, and arranged longitudinally between the two parts in a central line, and so as to bring the disk C close up against 45 the two parts, as seen in Fig. 2. On the top of the cork is a disk, E, through which the cord or wire passes, pressed upon the upper end of the cork with sufficient force to hold the two parts A and B between the two disks E C. 50 (See Fig. 2.) This completes the article.

The wire or cord D should be of sufficient length so as to be taken in the hand to withdraw the cork, or so that it may be engaged with something else to serve as a handle for drawing the cork, and thereby avoid the necessity of a corkscrew. This wire or cord may be used as a means for securing the cork in the bottle, as seen in Fig. 1, or where the bottle contains gases tending to force out the cork. This construction allows the stopper to be 60 made in several pieces, thus utilizing the smaller or thinner pieces of cork for making corks of larger size.

The wire loop may be applied to a stopper in one piece of common cork and have the advantage of securing the cork to the bottle as well as the means for withdrawing.

I do not broadly claim a bottle-stopper having a disk upon its lower end, in connection with the disk upon its upper end or with connections for applying or removing the stopper, as such, I am aware, is not new. Neither do I broadly claim a bottle stopper with a wire inserted longitudinally through it, secured at the lower end and formed into a loop at the 75 top, as a means for withdrawing the cork, as I am aware such device is not new.

What I do claim is—

1. A bottle-stopper provided with a loop of wire passing up through it and extending 80 from the upper end down on each side the bottle-neck, and with means for fastening the wire to the bottle, substantially as described.

2. A bottle-stopper composed of several longitudinal divisions of cork, combined with 85 a disk at each end and a connection longitudinally through the stopper, substantially as and for the purpose described.

3. A bottle-stopper composed of several longitudinal divisions of cork, combined with 90 a disk at each end and a connection longitudinally through the stopper, the said connection extended to serve as the means both for securing the stopper to the bottle and removing it therefrom, substantially as described.

EDMUND A. PARKER.
